UNITED STATES PATENT OFFICE.

ROBERT W. SCOTT, OF BOSTON, MASSACHUSETTS, ASSIGNOR TO SCOTT & WILLIAMS INCORPORATED, OF CAMDEN, NEW JERSEY, A CORPORATION OF NEW JERSEY.

NEEDLE-CARRIER AND NEEDLE FOR KNITTING-MACHINES.

1,221,806.

Specification of Letters Patent.

Patented Apr. 3, 1917.

Application filed August 31, 1914. Serial No. 859,349.

To all whom it may concern:

Be it known that I, ROBERT W. SCOTT, a citizen of the United States, and resident of Boston, in the county of Suffolk and State 5 of Massachusetts, have invented certain new and useful Improvements in Needle-Carriers and Needles for Knitting-Machines, of which the following is a specification.

This invention relates to needle carriers 10 and needles for knitting machines.

One object of my invention is to provide a needle bed, carrier, cylinder or dial with an improved inserted-wall structure providing grooves for independently movable 15 needles.

A further object is to provide said grooves with structures coöperating with independently movable needles to prevent the needles from being accidentally withdrawn from 20 their grooves.

In the accompanying drawings,

Figure 1 is a section transverse to the axis of a cylindrical needle carrier and needles therefor, on the line 1—1 of Figs. 25 9 and 10.

Fig. 1^a is an elevation illustrating one form of needle;

Fig. 2 is a section similar to Fig. 1 through a flat or straight bed or carrier;

Fig. 3 is a side elevation of a single inserted piece;

Fig. 4 is a side elevation of a modified form of insert;

Fig. 5 shows another modification;

Fig. 6 is a perspective showing the form of an inserted wall suitable for use in a dial or radial flat bed;

Fig. 7 is a section on line 7—7 of Fig. 4;

Fig. 8 is a section on the line 8—8 of 40 Fig. 5;

Fig. 9 is a sectional view showing the bottom or back of a needle in engagement with a needle groove formed by two inserts;

Fig. 10 is a similar view showing the co-action of a needle of a different form with one of the grooves.

In the usual forms of independent needle knitting machines, grooves for movement of the needles with respect to their carrier 50 by the action of cams on butts 1 of the needles are cut in the carrier, or formed

between walls inserted in grooves cut in the carrier, as well known in the art.

In the operation of such machines, especially of circular machines having automatic 55 cam devices, difficulty has been experienced in retaining the needles within their grooves during all of the operations. Various devices are familiar in the prior art for holding the needles in position, such, for instance, as endless rigid or spring bands encircling the cylinder, but such devices are necessarily located with respect to the needles at a point out of range of the reciprocal path of the needle-butt in its working 60 cycle.

The dimensions of the needles employed in such machines have grown progressively finer, increasing the resiliency of the needles, so that they are now often unable to resist 70 stresses tending to lift their lower or butt ends out of their grooves. Such stresses arise especially from the operation of the narrowing and widening devices or needle pickers, or from the employment of radially movable cams, especially when said devices move at high speeds.

In the case of dial knitting machines and flat bed knitting machines, stresses tending to lift the needles out of their grooves are 80 more common with stiffer, coarse-gage needles, generally being due to the leverage of the needles under the pull of the fabric.

I avoid the tendency of the butt end of the needles to be withdrawn from their 85 carrier by the devices shown in the drawings. As shown in Fig. 1, the needle cylinder 2 is provided with parallel grooves 3, in which are seated inserted walls or bars 4. Such walls or bars may be held in the cylinder 90 in any manner usual in the art, for instance by the engagement of their beveled ends with an under-cut groove and a beveled collar, such as described in the patent to Harry Swinglehurst No. 1,089,021, March 95 3, 1914. Such a bar may have the outline in elevation shown in Figs. 3 and 4.

In order to provide a substantially parallel-sided slot capable of guiding a needle formed from a blank of even thickness throughout, the gross cross-section of the inserts 4 may be wedge-shaped, as shown in 110

Fig. 1, although an insert of the parallel form shown in cross-section at 5 in Fig. 2 will be operative when applied to the surface of a cylinder. But of whatever shape 5 the general cross-sectional area of such walls may be made, I prefer to form them with one face 6 offset longitudinally of the bar to provide a shoulder 7, thus restricting the entrance of the groove formed between two 10 like inserts in width with respect to the width of the groove at a deeper part of said slot. This form may be given to the bars or inserts by rolling or drawing them, or the shoulder 7 may be formed by reducing or grooving the bar 4 along one face.

The shoulder 7 preferably will present a rounded surface or be formed at an angle not quite a right angle.

20 When the carrier is built up by the insertion of the bars 4 in the grooves 3 of the cylinder 2, the shoulder 7 will be at such a distance above the periphery or face of the carrier as to provide between said periphery 25 or face and said shoulder a space wide enough to freely receive the offset portion 10 of the needles 1, which may be formed in any convenient manner, as by bending said needles out of line through a part of their 30 length, as shown in Fig. 1^a, or by offsetting a tail or part of the needle, which may be reduced in thickness, as shown at 11, Fig. 10. The resilience of the needle will then enable it to be forced into its groove through 35 the restricted mouth thereof, or to be removed in the same way by the application of considerable force, but during their normal operation the needles will be held in their grooves by the engagement of their 40 portions 10 or 11 with shoulder 7. It will be noticed that the interlocking engagement of the needle is with a part near its butt, where the needle most needs support. For some uses an offset or bend 10^a, such as is 45 shown in Fig. 9, which is so short and stiff as to necessitate the removal of the needle endwise from its groove may be employed. Or when a needle of this type is to be employed, I may cut the offset face 6 away at 50 one end of the bar, preferably at a point beneath the range of reciprocation of the needle by the cams, as shown at 20, Fig. 9, to permit the needle to be moved out of its groove when the offset part 10^a is in a part 55 of the groove having no face 6 and no shoulder 7.

The structure shown in Fig. 2 for a straight or flat bed is similar to that shown in Fig. 1 except that there is in this case no occasion 60 for making the inserts 5 wedge-shaped. For either the situation of Fig. 1 or the situation of Fig. 2, I may form the insert or needle wall by another construction, but with the same effect, for instance, in the manner

shown in Figs. 4 and 7. In this form of my 65 device the wall is built up of plates 12 and 13, both of said plates being cut to the necessary form in elevation to enable them to be fastened in the grooves of the carrier. The plate 12 is flat or wedge-shaped in cross 70 section throughout its length, while the plate 13 is formed with a slot or window 14, the outer edge of which forms a shoulder similar to the shoulder 7, and for the same 75 purposes.

The slot 14 is of such width as to bring its lower edge at or below the level of the surface of the carrier in which it is inserted.

While in some situations the plates 12 and 13 are sufficiently stiff when merely locked 80 in place in the grooves 3, I prefer to attach them together by soldering, brazing, or, as illustrated in Figs. 4 and 7, by spot-welding at the points 15.

A similar structure results when, as shown 85 in Figs. 5 and 8 a flat bar 16 is similarly joined to a U-shaped section 17, as by brazing the two together as indicated at 18.

As shown in Fig. 6, I may apply my device to an inserted wall dial, for instance 90 such a structure as that shown in the patent to Harry Swinglehurst, No. 1,025,169, May 7, 1912, by forming the bars *x* of the said patent on one side thereof with overhanging ledge or shoulder 19 similar to the shoulder 95 7, to coöperate with the needles having offsets 10 or 11.

What I claim is:

1. In a knitting machine the combination 100 of needles having an offset portion with a needle carrier having inserted spacing walls for guiding the needles on the surface of said carrier, each wall having a surface interlocking with said offset portion of a needle to prevent movement of the needle away 105 from the carrier.

2. In a knitting machine a needle carrier having thereon spacing walls each having one plane surface and one surface presenting an overhanging shoulder, in combination 110 with independently movable needles held between said walls each having a lateral offset in engagement with one of said shoulders.

3. A needle carrier for knitting machines 115 having therein a system of parallel grooves, and inserted walls in said grooves each having an offset surface parallel with the direction of their greatest length, said surface being spaced away from the surface of the 120 carrier and overhanging the space between adjacent bars.

4. As an article of manufacture an insert 12 or wall for inserted-wall needle-carriers for knitting machines, consisting of a bar having a longitudinal shoulder on one face parallel with and near one edge thereof.

5. As an article of manufacture an insert

or wall for inserted-wall needle-carriers for knitting machines, consisting of a bar having at its ends a formation enabling it to be held in place, and having a longitudinal shoulder on one face parallel with and near one edge thereof.

In testimony whereof, I have signed my

name to this specification in the presence of two subscribing witnesses.

ROBERT W. SCOTT.
